US00D549230S

(12) **United States Design Patent** (10) Patent No.: **US D549,230 S**
(45) Date of Patent: **** Aug. 21, 2007**

(54) **SCANNER**

(75) Inventors: **Danni Luo**, Guan-Juo (CN); **Dasie Lei**, Guan-Jhou (CN)

(73) Assignee: **Lite-On Technology Corporation**, Taipei (TW)

(**) Term: **14 Years**

(21) Appl. No.: **29/252,089**

(22) Filed: **Jan. 19, 2006**

(30) **Foreign Application Priority Data**

Dec. 16, 2005 (TW) 94307739

(51) LOC (8) Cl. **14-02**

(52) U.S. Cl. **D14/421**

(58) **Field of Classification Search** D14/421-425;
D18/36-39, 55; 355/81, 75; 399/405, 367,
399/379, 380; 358/497; 235/470, 462.43,
235/482, 483

See application file for complete search history.
